UNITED STATES PATENT OFFICE.

MATHEW H. PAYNE, OF GLEN ELLYN, ILLINOIS, ASSIGNOR TO THE PAYNE COMPANY, OF CHICAGO, ILLINOIS, A CORPORATION OF ILLINOIS.

CEILING AND FLOOR PIPE PLATE.

Application filed March 3, 1926. Serial No. 91,944.

This invention relates to ceiling and floor pipe plates and has among its objects the provision of a novel and simple pipe plate having frictional means for retaining same in contact with the pipe.

Another object of the invention is found in the embodiment of resilient means for retaining a pipe plate or flange in fixed contact with the pipe; such means comprising a coil spring mounted on said plate in a manner to present the end portions of said spring for frictional contact with the pipe.

A further object of the invention resides in the provision of a triple support for the resilient retaining means; said triple support being formed integrally with the plate.

A still further object contemplates a pipe plate or flange construction having frictional retaining means and supports therefor concealed from exterior view of the plate.

With these and other objects in view, my invention consists in the novel combination, construction and arrangement of the parts and members shown in the accompanying drawings, described in the following specification and particularly pointed out in the appended claim.

Referring to the drawings, Figure 1, is an illustration showing the plate applied to a pipe at the ceiling;

Figure 2, is a section on line 2-2 of Figure 1, showing the plate in plan view;

Figure 3, is a bottom plan view showing the inner face of the plate and the resilient retaining members;

Figure 4, is a cross section taken on line 4-4 of Figure 3;

Figure 5, is an enlarged section taken on line 5-5 of Figure 4, showing the clasp arrangement for the two half sections of the plate;

Figure 6, is a cross section taken on line 6-6 of Figure 3;

Figure 7, is a plan view of one of the retaining coil springs;

Figure 8, is a plan view of the inner face of a plate with a modified arrangement of the spring supports and a comparatively large central opening for pipes of greater diameter than that illustrated in Figures 1 to 6 inclusive.

Referring to the drawings in more detail, the plate generally designated by 10 com-

prises a pair of semi-circular sections 11 and 12 each formed with an outwardly extending head 13 having an inwardly disposed upward flange 13^A defining the pipe opening 14. Each section 11 and 12 is also formed with an inwardly disposed right-angled flange 15.

The sections 11 and 12 are hinged together for movement about the pivotal rivet 16 having heads embracing the pivotal ears 17 and 18 formed integrally with the sections 11 and 12. A portion of the flange 15 is slightly deformed as at 15^A to permit the opening of the sections apart as shown by dotted lines in Figure 3, preceding the embracement of the plate over the pipe 19.

The sections 11 and 12 are also formed with overlapping integral ears 20 and 21 constituting a clasp; the ear 20 having a punched outlip 20^A adapted for movement into the opening 21^A of the inwardly depressed portion of the ear 21. To facilitate the lateral displacement of the sections in closing the ear 21 is formed with an angularly bent end 21^B affording an inclined surface for sliding engagement by the lip 20^A preceding its entrance into the opening 21^A.

The flange 13^A is formed with a plurality of integral spring supports 22 of T formation; the upper portion 22^A being wider than the integral neck portion 22^B. The upper portion 22^A forming armlike projections which act as stops for the ends 23^A of the coil springs 23; the loop or coil portion 23^B of the springs being confined on one of the supports 22.

When the plate 10 is inserted around the pipe 19 and snapped into closed position, as shown in Figure 2, the sides of the spring ends will contact with the pipe and will due to their resilient action exert pressure on the side of pipe and frictionally retain the plate 10 thereon.

In the device shown in Figures 3, 6, and 8, two opposite supports 22 fall on the center line dividing the two hinged sections 11 and 12 and therefore each of these supports 22 is divided into two half sections, one section of each support being formed integrally with flange 13^A on section 11 and the other integrally with the flange 13^A of section 12, as clearly shown in Figure 6. However, if the plate be designed for a pipe

of larger diameter, as shown in Figure 8, then the supports 22' for the spring ends may be spaced as shown and may consist only of an inverted L formation as only one 5 spring end is confined thereon.

The drawings herein illustrate a preferred embodiment of the invention, and various ways of changing the details or arrangement of the parts shown may readily become apparent, hence I do not wish to limit myself to the particular construction shown but 10 wish to include all changes and rearrangements falling within the scope of the invention as defined by the appended claim.

15 I claim:

A pipe plate comprising a pair of semi-annular hingedly connected sections, means for retaining said sections in closed position, said sections when in closed position being

adapted to circumferentially embrace a pipe, 20 a plurality of supports formed integrally with the inner circumferential edges of said sections, said supports being bent angularly to the plane of said plate sections and comprising a neck portion and a head portion 25 wider than said neck portion, a plurality of coil springs mounted on said supports, each of said coil springs having its end portions extended in angular relation to each other and the end of each of said spring end portions being confined between said neck and head portions of said supports, said spring end portions extending within the opening 30 defined by said plate sections whereby the side of said pipe will be frictionally engaged 35 by said spring end portions.

In witness whereof I affix my signature.
MATHEW H. PAINE.
